UNITED STATES PATENT OFFICE.

HERMAN RUDNICK, OF NEW YORK, N. Y., ASSIGNOR TO F. RUDNICK, INC., A CORPORATION OF NEW YORK.

CONTAINER.

1,209,040.

Specification of Letters Patent. Patented Dec. 19, 1916.

Application filed March 9, 1915. Serial No. 18,223.

To all whom it may concern:

Be it known that I, HERMAN RUDNICK, a citizen of the United States, and a resident of New York, borough of Bronx, county of Bronx, and State of New York, have invented a certain new and useful Improvement in Containers, of which the following is a full, clear, and exact specification.

This invention relates more particularly to a class of boxes having open tops.

My invention has for its object primarily to provide a form of container designed to be utilized for packing merchandise therein, especially dry cell batteries, so as to be attractive in appearance when offered for sale as well as tending to prevent the contents from being damaged when transported, and which is of a form whereby the requirement for making the body of the container and its bottom separately may be dispensed with, thus serving to prevent the bottom from becoming displaced from the body as is incident to other makes of such types of containers.

The invention consists essentially of a supporting body formed from a single blank of cardboard, or other like flexible material which is cut to provide a substantially rectangular member, or plate, a substantially elliptic bottom member or plate integral with the rectangular member and extending from the central part of the lower edge thereof, and also a substantially rectangular tongue, or extension integral with the elliptic bottom member and extending therefrom in an opposite direction to the rectangular member, the supporting body being provided by forming the rectangular member into an approximately elliptic tubular wall and then disposing the bottom member and the rectangular extension upwardly so that the bottom member will close the adjacent end of the tubular wall and the extension will be guided interiorly of the tubular wall for the ends of the rectangular member to be pasted or otherwise connected thereto.

Other objects of the invention are to provide on the lower edge of the rectangular member and between the bottom member and its ends two small fingers which are turned over the underside of the curved ends of the elliptic bottom member when the supporting body is assembled to provide for the supporting body a covering made from a single blank of paper, or other like material

cut to provide a substantially rectangular member, and an integral substantially elliptic bottom member, both of these members corresponding in shapes and sizes as well as in relative arrangement to the similar parts of the supporting body and to provide on the covering marginal extensions adapted to be disposed so as to overlap the adjacent edges of the body when the covering is applied thereon.

A further object of the invention is to provide a container of simple and efficient form which may be made to combine exceptional strength and durability.

A practical embodiment of the invention is represented in the accompanying drawings forming a part of this specification in which similar characters of reference indicate corresponding parts in all the views, the said invention being more fully described hereinafter, and then pointed out in the claims at the end of the description.

In said drawings Figure 1 is a perspective view of a container embodying my invention, and Fig. 2, is a plan of the blank from which the container shown in Fig. 1 is formed.

Referring to said drawings, the container comprises a supporting body 17 made from a single blank cut to provide a substantially rectangular wall member 18 adapted to be curved vertically so as to form a partial tubular wall, and projecting from the central part of the lower edge of this rectangular member is an integral substantially elliptical bottom member 19 which is disposed lengthwise of the rectangular member longitudinally thereof, and this bottom member is of a size adapted to close the adjacent open end of the tubular wall when formed. Extending from the second lengthwise edge of the bottom member 19 in an opposite direction to the rectangular member 18 is an extension or wall member 20 which is of a length similar to the height of the rectangular member, and this extension is of a width adapted to permit the ends of the rectangular member to overlap thereon for closing the space between the ends of the rectangular member when curved to provide the tubular wall of the supporting body. When these parts are assembled to form the supporting body 17, the rectangular member 18 is formed into a partially substantially elliptic wall, and the elliptic

bottom member 19 is turned upwardly to a like plane with the lower edge of the rectangular member to close the adjacent end thereof. The extension 20 is likewise disposed upwardly from the bottom member for being guided so that the ends of the rectangular member will overlap the vertical edges of the extension, and the supporting body will then be formed by sealing together the rectangular member and this extension. To connect the free curved ends of the elliptic bottom member 19 to the elliptic tubular wall of the supporting body, projecting from the lower edge of the rectangular member 18 of the blank at its ends, are two integral tongues 21 and 22. When the supporting body 17 is formed, as described the tongues 21 and 22 are turned over on the underside of the curved ends of the bottom member 19 and may be sealed thereto.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope of the appended claims.

Having thus described my invention, I claim as new and desire to secure by Letters Patent:—

1. A blank for containers comprising an approximately elliptical bottom member having substantially parallel edges, a substantially rectangular wall member integral with one edge of said bottom member and of sufficient length to extend completely around the ends thereof when disposed transversely thereto, a second wall member integral with the other parallel edge of said bottom member and adapted when disposed transversely thereto to lie in overlapping relation to said first mentioned wall member, the opposed surfaces of the said wall members overlapping whereby a joint may be formed therebetween, and integral fingers provided on the first mentioned wall mem-

ber and adapted to be folded under the ends of the bottom member to support the same when the container is in assembled position, substantially as described.

2. A blank for containers comprising an approximately elliptical bottom member having substantially parallel edges, a substantially rectangular wall member integral with one edge of said bottom member and of sufficient length to extend completely around the ends thereof when disposed transversely thereto but leaving an uninclosed space between the two adjacent edges of the wall member, and a second wall member integral with the other parallel edge of the bottom member and adapted when disposed transversely thereto to close the open space between the adjacent edges of the first mentioned wall member, thereby forming a container, substantially as described.

3. A blank for containers comprising an approximately elliptical bottom member having substantially parallel edges, a substantially rectangular wall member integral with one edge of said bottom member and of sufficient length to extend completely around the ends thereof when disposed transversely thereto but leaving an uninclosed space between the two adjacent vertical edges of the wall member, a second wall member integral with the other parallel edge of the bottom member and adapted when disposed transversely thereto to close the open space between the adjacent edges of the first mentioned wall member, the opposed edges of the first and second wall members overlapping, whereby a joint may be formed therebetween, and integral fingers provided on the first mentioned wall member and adapted to be folded under the ends of the bottom member to support the same when the container is in assembled position, substantially as described.

This specification signed and witnessed this eighth day of March A. D. 1915.

HERMAN RUDNICK.
